United States Patent Office

Des. 179,247
Patented Nov. 20, 1956

179,247

INDOOR ANTENNA CABINET

Henry D. Halperin, New York, N. Y., assignor to General Bronze Corporation, Garden City, N. Y., a corporation of New York

Application July 15, 1955, Serial No. 36,984

Term of patent 3½ years

(Cl. D26—14)

Fig. 1.

Fig. 2.

Fig. 3.

Figure 1 is a front perspective view of an indoor antenna cabinet, showing my new design.

Figure 2 is a rear elevational view of the indoor antenna cabinet shown in Figure 1.

Figure 3 is an end elevational view of the indoor antenna cabinet.

I claim:

The ornamental design for an indoor antenna cabinet, substantially as shown.
